HERMETICALLY SEALED ELECTROMAGNETIC RELAY

Ronald V. Tetz, Los Gatos, Calif., assignor to Jennings
Radio Manufacturing Corporation, San Jose, Calif., a
corporation of Delaware

Filed July 13, 1964, Ser. No. 80,826

Term of patent 14 years

(Cl. D26—13)

FIG. 1

FIG. 3

FIG. 2

FIG. 4

FIG. 5

FIG. 6

FIG. 7

FIG. 1 is a top plan view taken in the direction of the arrow 1 in FIG. 2;

FIG. 2 is a front elevational view taken in the direction of the arrow 2 in FIG. 1;

FIG. 3 is a top plan view similar to FIG. 1 but rotated 180°;

FIG. 4 is an elevational view taken in the direction of the arrow 4 in FIG. 3;

FIG. 5 is a side elevational view taken in the direction of the arrow 5 in FIG. 4;

FIG. 6 is a bottom view taken in the direction of arrow 6 in FIG. 5;

FIG. 7 is a perspective view of the hermetically sealed electromagnetic relay.

I claim:

The ornamental design for a hermetically sealed electromagnetic relay, as shown and described.
